UNITED STATES PATENT OFFICE.

WILLIAM H. RODEFELD, OF RICHMOND, INDIANA.

POWER-TRANSMITTING APPARATUS.

1,117,446.

Specification of Letters Patent. Patented Nov. 17, 1914.

Application filed December 20, 1913. Serial No. 807,840.

To all whom it may concern:

Be it known that I, WILLIAM H. RODEFELD, a citizen of the United States, residing in the city of Richmond, in the county 5 of Wayne, and in the State of Indiana, have invented a new and useful Power-Transmitting Apparatus, of which the following is a full, clear, and comprehensive specification, being such as will enable a mechanic to 10 make and operate the same with precision.

This present invention relates to a power transmitting mechanism constructed on substantially the same principles as that of my former invention which was set forth in my 15 application filed June 30th, 1913, Serial No. 776,488, allowed Nov. 17, 1913, but incorporating, in this instance, certain features whereby the driven element may be rotated reversely to that of the driving element.

The object herein attained is the provision of a gearless and practically frictionless apparatus for transmitting power reversely to that of the driving shaft, at the 25 same time providing an apparatus which will be noiseless in operation, practically indestructible in use, and adapted to transmit a smooth and even change of direction regardless of proper manipulation on the 30 part of the operator.

Other special objects and advantages of my present invention will be brought out in the course of the following specification.

It should be remembered that the principles of my invention may be carried out in a variety of ways, but that which I have determined to be the most practical is shown in the accompanying one-sheet of drawings, in which—

40 Figure 1 is a perspective view, partly in section, of the construction incorporating my invention. Fig. 2 is a vertical section, taken centrally through the construction shown in Fig. 1. And Fig. 3 is a detailed 45 perspective view of the spool and the spindle or driven element, which is integral therewith.

Similar indices denote like parts throughout the several views.

50 Referring now to the invention in detail: Numeral 1 denotes the base, from which extend upwardly the two separated standards 2 and 3, each carrying on its upper ex-

tremity the respective bearings 4 and 5 which are in horizontal alinement with each other. Revolubly mounted in the bearings 4 and 5 is the shaft 6, constituting the driving element. Formed integral with, or rigidly secured on, the shaft 6 between the bearings 4 and 5 is the boss 7 which is concentric with the shaft 6, and whose length is less than the distance between the bearings 4 and 5 for reasons hereinafter made apparent. Secured to the standards 2 and 3 and extending across therebetween and located near the base 1, is the bar 8 on which the lower portion of the clamping-ring is hinged. Said clamping-ring comprises the two segmental members 9 and 10, whose lower ends are interlocked where they are concentrically pivoted on the bar 8, substantially as shown. Extending up from the upper end-portion of member 9 are the two spaced-apart ears 11 and 12. And in like manner extending up from the upper end portion of member 10 is the ear 13. Mounted between the ears 11 and 12, on the pivot 15, is the angular lever 16 which extends upward and forward as shown. Mounted on the ear 13, by the pivot 17, is the link 18, the upper or forward end of which is pivoted to the upwardly extending end of the lever 16 on the fulcrum 19 carried by said lever. By the above described construction it will be apparent that when 85 the lever 16 is turned in one direction on its fulcrum 19 the upper ends of the members 9 and 10 will be brought toward each other, while if the said lever is moved in the opposite direction the said members will be 90 moved apart, for the purposes hereinafter made apparent. Revolubly mounted around the boss 7 is the spool which comprises the two end disks 20 and 20', which are integrally connected near their peripheries by 95 the bars 20''. Formed in the edges of the disks 20 and 20', cutting the peripheries thereof, are a plurality of notches b, in this instance there being six of said notches in each disk. Formed through the center of 100 the disk 20' is the aperture a, whose diameter is slightly greater than is the diameter of the boss 7 which may pass therethrough as the device is being assembled or taken apart. Extending out 105 from the center of the disk 20 is the hollow

spindle 23, which forms the driven element of the device, there also being a central aperture through the disk 20 which corresponds with and forms a continuation of 5 the aperture through said spindle.

A plurality of rollers 21 are spaced apart from each other and they are located parallel with each other and with the shaft 6. Said rollers 21 are of such length as to fit 10 between the disks 20 and 20', and their lengths are the same as is the width of the members 9 and 10. Extending out in an axial direction from the center of each end of each of the rollers 21 are the pivots *c*, 15 which are concentric with their respective rollers. Each of said rollers 21 is mounted both to revolve and to move radially, to attain which there is slidably mounted in each of the notches *b* a bearing or guide-block 22, each having a central aperture therethrough for the pivots *c* of the rollers 21. Each of said guide-blocks is provided 20 on two of its edges with lips *x*, whereby it is prevented from working outward said 25 lips acting as guides for the blocks as they move in and out in their notches *b*. The spindle 23 is journaled in the bearing 5, and the shaft 6 extends therethrough, whereby the bearing 5 provides a support both for 30 the shaft 6 and the spindle 23, as shown in Fig. 1. A plurality of rollers *A* are located between the boss 7 and the rollers 21, the same being parallel thereto and contacting therewith, as indicated in Fig. 2. The 35 rollers *A* are of the same length as the rollers 21, but they have no pivots on their ends, but their ends are adapted to contact with the inner faces of the disks 20 and 20', which prevents them from being displaced 40 laterally. The relative size of the boss 7, the rollers 21, and the rollers *A* may be variously changed to meet various conditions or desiderata, depending upon the speed at which it is desired the spindle or 45 driven element is to travel with relation to the shaft or the driving element. It is contemplated that a pulley, gear, sprocket, or the like (not shown) may be secured on the spindle 23, through which power may 50 be transmitted to a machine or the like.

It will be observed that the various elements may be assembled as in Figs. 1 and 2. If now the shaft 6 be rotated in either direction, with the lever 16 turned upward 55 to its limit of movement, it is evident that the spindle 23 will remain at rest. But if the lever 16 be now moved forward, to the position in which it is shown in Figs. 1 and 2, the upper ends of the members 9 and 10 60 of the clamping ring will be brought toward each other, thereby clamping the members 9 and 10 upon the rollers 21, and they in turn upon the rollers *A*, thereby pressing the latter into contact with the boss 7. 65 Therefore the rollers *A* will revolve on the

periphery of the boss 7 and also upon the rollers 21, thereby causing the rollers 21 to revolve upon the rollers *A* and upon the inner face of the members of the clamping-ring.

The operation just described will eventuate to revolve the spool, and consequently the spindle 23, in a reverse direction to that of the shaft 6, thereby accomplishing the 70 primal object of this invention.

It should be understood that this invention may be employed in connection with other devices for operating the driven element at various speeds with relation to the driving element, such as that shown in my 80 former invention above referred to.

I desire that it be understood that various changes may be made in the several details of construction from that herein set forth, the parts may be differently arranged, and the proportionate sizes of the several parts may be varied therefrom, without departing 85 from the spirit of this invention and without sacrificing any of the advantages thereof.

Having now fully shown and described my invention, what I claim and desire to secure by Letters Patent of the United States is—

1. An apparatus of the nature set forth comprising a shaft having a boss carried thereby and concentric therewith, a spool concentric with the boss, a plurality of outer rollers mounted and radially movable in said spool, a plurality of inner rollers loosely located between the boss and the outer rollers, a clamp surrounding the spool, means for contracting said clamp upon the outer set of rollers whereby the spool will be rotated reversely to the shaft. 90

2. An apparatus of the nature set forth comprising a shaft having a boss carried thereby, a spool concentric with the boss, a spindle surrounding the shaft and rigidly connected to the spool, a plurality of outer rollers mounted to revolve and movable radially in said spool, a plurality of inner rollers loosely located between the boss and the outer rollers, a clamp surrounding the outer rollers and adapted to contact with the outer set of rollers to press the clamp, the outer set of rollers, the inner set of rollers, and the boss into rolling contact with each other whereby the spindle will revolve in a direction opposite to that of the shaft. 105

3. An apparatus of the nature set forth comprising a rotatable shaft having a boss forming an enlargement of a portion thereof, a spool concentric with said boss, a spindle surrounding the shaft and formed integral with the spool, a clamping-ring, an outer set of rollers carried by the spool and radially operable therein and adapted to revolve on the inner face of the clamping- 110

ring, an inner set of rollers adapted to revolve in contact with the outer set of rollers and with said boss, and means for opening and closing the clamping-ring to place it in and out of contact with the outer set of rollers.

In testimony whereof I have hereunto

subscribed my name to this specification in the presence of two subscribing witnesses.

WILLIAM H. RODEFELD.
